UNITED STATES PATENT OFFICE.

HARRIETTE E. HODGSON, OF NEW YORK, N. Y.

PORTABLE DRESSING TENT.

Application filed May 24, 1922. Serial No. 563,249.

To all whom it may concern:

Be it known that I, HARRIETTE E. Hodgson, a citizen of the United States, and a resident of the borough of Manhattan, in the city, county, and State of New York, have invented a new and useful Portable Dressing Tent, of which the following is a specification.

This invention relates to tents or the like, and the particular object is to provide a small and conveniently portable dressing enclosure for use by bathers. This dressing tent comprises a framed top adapted to be supported upon the person, and a depending enclosure, which is sufficiently roomy to permit the user to dress and undress within it. Means are provided within the enclosure for holding clothing, and other features will also appear. The enclosure can also be used with a pole as a sunshade, or it can be suspended from the branch of a tree or other available overhead support. When not in use, the tent can be folded into small compass for carrying.

In the accompanying drawings forming a part hereof:

Fig. 1 is a side elevation of my dressing tent in use;

Fig. 2 is a view looking upward;

Fig. 3 is a vertical section on the line 3-3 of Fig. 2;

Fig. 4 is a fragmentary detail view;

Fig. 5 is a front elevation, showing the tent used with a pole, with the front flaps fastened back;

Fig. 6 is a view looking up, showing the opening in the top closed with the flap provided for this purpose; and

Fig. 7 is an elevation on a smaller scale, showing a different manner of attaching the tent to the person.

The dressing tent illustrated in these views has a rectangular top frame 1, composed of light members suitably disposed and united to each other to form a sufficiently strong and rigid frame. This frame is covered with fabric 2, except for a central opening 3, large enough to admit the head of an occupant. This opening can be closed by a flap 3^a, which is usually folded back and secured by snap-fastener elements 4, as seen in Figs. 2 and 3. When disposed across the opening, as in Fig. 6, the flap is secured by other snap-fastener elements 5. Extending across the opening 3 and secured at both ends to the top is a strap 6, which is sufficiently

long to curve slightly up or down above or below the plane of the top, as the case may be. Secured centrally for a distance to this strap is another strap 7, presenting two free ends. The construction is such that the strap 6 can either be passed beneath the chin and the ends 7 tied over the top of the head, as seen in Fig. 1, in which event the head or eyes of the occupant are above the level of the top, or else the strap 6 can be passed over the top of the head and the ends 7 tied beneath the chin, with the result that the occupant's eyes are below the level of the top.

The top frame is preferably hinged on a central transverse axis, as indicated at 8, so that it can be folded in half for carrying, suitable catches or bolts 9 being provided for locking the frame when folded out flat.

Connected with the edges of the top frame 75 is a depending enclosure 10, consisting of back and side walls of fabric and a front wall comprising two flaps 11 which can be folded back and tied with tapes 12, 13, as illustrated in Fig. 5. This enclosure is 80 adapted to come down to or substantially to the ground and for extra security its lower edge may be fastened down by pegs 14 connected with the lower part of the enclosure by tapes 15, the pegs being adapted to be 85 driven into the sand or ground, as indicated in Fig. 5. Commodious pockets 16 are arranged on the inner sides of the enclosure walls, in which to place garments.

The manner of using the dressing tent 90 will be readily understood from the drawings and more particularly by reference to Figs. 1 and 7. In some cases, instead of strapping the top frame onto the head, the opening 3 may be simply passed over the 95 head and the frame members surrounding it allowed to rest upon the shoulders. In some cases the tent can be suspended by the straps 6 and 7 from the limb of a tree, and it will be understood that the tent can also 100 be used by children or adults for other than dressing or bathing purposes. In some cases it will be desired to support the tent either in a vertical position or in a rearwardly inclined position by means of a central pole 105 17. The upper end of this pole passes through a hole 18 in the closed flap 3^a (Fig. 6), and its upper end rests against the strap 6 whereby the top is suspended. In connection with the pole and with the front flaps 11 fastened back, the tent is serviceable as a 110 sun shield for beach use.

What I claim as new is:

1. A dressing tent having a framed top containing an opening for the head and provided with means for supporting it upon a person in a standing position and a depending enclosure.
2. A dressing tent having a framed top having means for securing it to the head of an occupant, and a depending enclosure adapted to come to the ground or substantially so when so supported.
3. A dressing tent having a framed top having an opening for the head of an occupant and strap means for supporting it upon the head, and a depending enclosure.
4. A dressing tent having a framed top

with means for supporting it upon the person, a depending enclosure, and pockets upon inner sides of the walls of the enclosure.

5. A dressing tent having a framed top having an opening for the head of an occupant and provided with means for supporting it upon the occupant in a standing position, a depending enclosure, and a flap for closing said opening, said flap being adapted to receive a pole.

6. A dressing tent having a framed top having means for supporting upon the person and hinged so as to fold, and a depending enclosure.

HARRIETTE E. HODGSON.
